UNITED STATES PATENT OFFICE.

WILLIAM C. CODMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

45,614.

Specification for Design.

Patented Apr. 21, 1914.

Application filed February 25, 1914. Serial No. 821,005. Term of patent 14 years.

To all whom it may concern:

Be it known that I, WILLIAM C. CODMAN, a subject of the King of Great Britain, residing at Providence, in the county of Providence and State of Rhode Island, have invented a new, original, and ornamental Design for Handles for Spoons, Forks, or Similar Articles, reference being had to the accompanying drawings.

Figure 1 is a view of the obverse side of the handle, showing my design. Fig. 2 is a view of the reverse side of the handle. Fig. 3 is an enlarged detail perspective view.

I claim—

The ornamental design for a handle for spoons, forks or similar articles, as shown.

WILLIAM C. CODMAN.
